UNITED STATES PATENT OFFICE.

ROBERT LIVINGSTONE LOCKERBIE, OF EAST INVERCARGILL, NEW ZEALAND.

SASH-BALANCER.

SPECIFICATION forming part of Letters Patent No. 782,974, dated February 21, 1905.

Application filed January 20, 1904. Serial No. 189,852.

To all whom it may concern:

Be it known that I, ROBERT LIVINGSTONE LOCKERBIE, carpenter, of Mary street, East Invercargill, New Zealand, have invented certain new and useful Improvements in Sash-Balancers, of which the following is a specification.

This invention relates to that class of sash-hangers consisting of a roller in or round which a spiral spring is wound, mounted revolvably in bearings in a window-frame or the like, and adapted to wind up cords secured to a sash or sashes.

A leading feature of the invention is the specially-constructed telescoping roller, hereinafter described, whereby its length may be readily adjusted to suit different widths and such that it may be readily removed from and fixed in its bearings. Another feature is the continuous cord extending from one end of said roller to the other end thereof, running round pulleys one at or near each end of the top rail of a sash, whereby evenness of hanging of the said sash is secured.

The invention consists in these features and in the combination and arrangement of parts hereinafter described, all more particularly pointed out in the claim.

In the accompanying drawings the same reference letters and numerals indicate the same or similar parts.

Figure 1 shows the apparatus fitted up for hanging a sash. Fig. 2 illustrates the method of connecting the cord to the sash. Fig. 3 is a plan view looking upward to the apparatus fixed overhead. Fig. 4 is a cross-section through the cover and spring *ab*, Fig. 1, showing the casing fitted in a window-stile. Fig. 5 shows a pulley in a groove in a sash. Fig. 6 shows the loose spindle drawn out for taking the roller out of the bearings.

There is a telescoping roller consisting of three portions—namely, a hollow spindle 1, into which fits slidably a loose spindle 2, the other end of said loose spindle 2 also fitting slidably into another spindle, 3, to which it is secured by a set-screw 4. By these arrangements the length of the roller can be adjusted to suit the width of the window or other frame. The outer ends 5 6 of the spindles 1

and 3 are respectively journaled in bearings 50 7 8, secured, respectively, to the sides 9 10 of a window-frame or the like.

Circular flanges 11 12 are secured to the outer end of the spindle 1 at a short distance from each other, forming a reel 13, to which 55 one end of a cord 14 is secured, so that it may be wound round said reel by the revolution of the roller.

A spiral spring 15 is wound round the spindle 1, one end, 16, of said spring being secured 60 thereto and the other end, 17, to a D-shaped casing 18, surrounding the spring 15 and the spindle 1, so that the spring 15 is tightened or released by the revolution of the spindle 1. The spring is primarily tightened to the degree required, according to the weight of the sash, by turning the casing or the spindle round. Secured to the casing 18 is a locking-bolt 19, which is adapted to slide into a slot 20 for the purpose of locking the spring 70 15 after it has been wound up to the desired strength. Circular flanges 21 22 are secured to the outer end of the spindle 3 at a short distance from each other, forming a reel 23, to which the other end of the cord 14 is secured, so that it may be wound around said 75 reel by the revolution of the roller. The cord 14 passes from the reel 13 under a pulley 24, mounted, preferably, in a groove in the top rail 25 of a sash at one end thereof, thence 80 along said groove and under another pulley, 26, similarly mounted at the other end of the rail 25, and upward to the reel 23. By this arrangement of the cord the sash is hung evenly balanced. In operation the cord 14 is 85 secured by one end to the reel 13 and passed underneath the pulleys 24 and 26, and the other end of the cord is secured to the reel 23. One end of the loose spindle 2 is inserted 90 within the hollow spindle 1, and the other end is inserted within the spindle 3. The spring 15 is wound up to the strength required to raise the sash easily with a slight assistance by the hand by turning the roller or the casing, and it is then locked by the locking-bolt 95 19 being inserted in the slot 20. The outer ends 5 and 6 of the spindles 1 and 3 are then respectively inserted in the bearings 7 and 8,

and the spindles 1 and 3 are drawn apart, so that the roller fits the frame. The set-screw 4 is then tightened, clamping the loose spindle 2 to the spindle 3. The casing 18 is prevented from revolving by the face of plate 26 engaging against the edges of an opening in the stile 27. When two sashes are to be hung one above the other, as in the case of a window, two sets of the apparatus are used, one being secured alongside the other, as before described. The roller may be secured upside down to the top rail, and the cord is then fitted to run in pulleys in a groove in the stile or frame.

15 The bolt 19 is withdrawn from the slot 20 as soon as the sash is attached to the cords, so as to allow the roller and spring to operate, the weight of the sash preventing the spring from unwinding too quickly. The bolt is 20 only used as a lock when the roller is to be taken down, when it is down, and when it is being put back into place, its purpose being

to prevent the spring from unrolling when the weight of the sash is taken off it.

Having now particularly described my invention, I declare that what I claim as new, and desire to secure by Letters Patent, is—

In combination a roller consisting of three portions the two exterior portions being hollow spindles and the central portion being a loose 30 spindle slideable in said hollow spindles, a set-screw, bearings for the outer ends of said hollow spindles, two circular flanges on each hollow spindle, a spiral spring on one hollow spindle, a casing surrounding said spring and spindle, and a locking-bolt between the casing and an adjacent flange.

In testimony whereof I have hereunto set my hand in presence of two witnesses.

ROBERT LIVINGSTONE LOCKERBIE.
